UNITED STATES PATENT OFFICE.

RAYMOND H. SMICKLE, OF BELVIDERE, NEW JERSEY, ASSIGNOR TO INGERSOLL-RAND COMPANY, OF JERSEY CITY, NEW JERSEY, A CORPORATION OF NEW JERSEY.

BROACHING ATTACHMENT.

Application filed March 3, 1926. Serial No. 91,965.

This invention relates to fluid actuated rock drills, but more particularly to a broaching attachment which may be substituted for the ordinary front head of a fluid actuated rock drill of the hammer type.

The objects of this invention are to enable a flat rectangular broaching tool to be held and guided in a rock drill in an improved and simplified manner, and to enable the broaching tool to be quickly inserted into the front head of the drill and removed therefrom.

Other objects will be in part obvious and in part pointed out hereinafter.

The invention consists of the combination of elements, arrangement of parts and features of construction substantially as herein-after described and more particularly pointed out in the appended claims and illustrated in the accompanying drawings, in which—

Figure 1 is an elevation partly in section of the front end of a rock drill equipped with an attachment constructed in accordance with the practice of the invention,

Figure 2 is a sectional elevation taken through Figure 1 on the line 2—2 looking in the direction of the arrows, and

Figure 3 is a transverse view in section taken through Figure 2 on the line 3—3 looking in the direction of the arrows.

Referring to the drawings, the invention is shown embodied in a rock drill of which only a front portion of a cylinder A is shown. A bushing B inserted in the front end of the cylinder A forms a head for the cylinder and also acts as a guide for the nose or extension C of the piston (not shown) reciprocable in the cylinder A.

In accordance with the present invention, an attachment or front head D is supported by the cylinder A and preferably secured thereto by means of a pair of cushioned side bolts E which extend through lugs F and G carried by the cylinder A and the front head D respectively. The bolts E are provided with springs H which bear against the lugs G of the front head D to hold said front head yieldably within the cylinder A.

The rearward portion of the front head D is preferably of generally cylindrical formation and is provided with a bore J which acts as a guide for an anvil block K interposed between the piston nose C and a broaching tool L for transmitting the blows

of the hammer piston to the broaching tool. The rearward portion of the bore J is preferably enlarged somewhat for the reception of a bushing O which forms a removable guide for the extension C of the hammer piston.

The front end of the front head D is preferably rectangular as at P and is provided with a rectangular recess Q having parallel walls and into one side of which recess is arranged a jaw R preferably held in fixed position by means of suitable screws S. The jaw R is seated on a front end wall D' of the front head D and in this instance is provided at its innermost end with a projection portion T adapted to extend into a groove U formed in the side of the broaching tool L near the rearward end thereof. Disposed on the opposite side of the recess Q is another jaw V which, like the jaw R, is also provided with an inwardly extending projection T near its rearward end to extend into a groove W formed on the broaching tool L opposite to the groove U.

In order that the broaching tool L may be quickly released from the front head D, the jaw V is adapted to be actuated slidably on the wall D' toward and away from the broaching tool L. To obtain this slideable movement of the jaw V, a wedge-like member X is disposed in the recess Q to slide in a plane parallel to the longitudinal axis of the front head and to cooperate slidably with a tapered surface Y of the jaw V. The wedge X is provided in this instance with a T-slot Z which engages a T-shaped projection b formed longitudinally of the jaw V on the tapered side Y. The wedge X is preferably considerably shorter than the jaw V so that it will be capable of a wide range of movement in a longitudinal direction in the recess Q. Any suitable means may be provided for locking the wedge X in placed position. In the present instance a bolt c is inserted through the wedge and extends through a slot d formed longitudinally of the front head and carries on its outer end a nut e whereby the wedge X, and consequently the jaw V, may be locked in position.

In the present instance the jaws R and V are provided with suitable surfaces f and g respectively which cooperate with the sides of the broaching tool L for guiding said tool. An opening h is formed in the front end wall D' of the front head D to permit

the insertion of the broaching tool L into said front head. The opening h is preferably of ample width so that the jaws R and V and the wedge X may pass freely there- 5 through in assembling or disassembling the device.

In assembling the jaws and wedge in the front head D, the bolt c and the wedge X may first be inserted through the opening 10 h of the front head into the recess Q. The wedge and the bolt may then be moved to their approximate assembled positions to enable the T-shaped projection b of the jaw V to be inserted in the T-shaped slot Z 15 of the wedge X. After the wedge and the jaw V have been thus interlocked, the jaw can be moved upwardly into the recess Q until its outermost end clears the end wall D' by which it is supported.

20 In Figure 2 the adjustable jaw V is shown in its tool engaging position. In this position of the jaw V, it will be noted that the guiding faces f and g engage the sides of the broaching tool, it being intended in this 25 position of the jaw V that there be only sufficient clearance between the jaw and the broaching tool to permit free reciprocation of said broaching tool. If, however, it be found desirable to provide greater clearance 30 between the guiding surfaces of the jaws in the broaching tool, the wedge X may be drawn slightly rearwardly in the recess Q. Movement of the wedge in this direction will have the effect of withdrawing the jaw V. 35 After the jaw V has been moved to the desired position, the nut e may be tightened on the bolt c and the jaw will be held firmly in position.

To release the broaching tool L, the wedge 40 X may be moved rearwardly along the tapered side Y of the jaw V until a space exceeding the thickness of the tool is formed between the projections T of the jaws, whereupon the broaching tool L may be removed from the front head. After the jaw 45 V has been moved to its releasing position, the nut e may be tightened on the bolt c and the jaw V will remain in releasing position ready for the insertion of another 50 broaching tool.

By means of this invention the broaching tool may be quickly inserted into the front head or removed therefrom in practically the same manner as a drill steel may be 55 inserted in the ordinary type of front head.

The parts, in this instance, the jaws R and V, which serve as guides for the broaching tool L may be readily and cheaply replaced and owing to the fact that the jaw V is adjustable, any wear which may occur on 60 the jaws may be quickly compensated for by merely advancing the jaw V in the direction of the broaching tool.

I claim:

1. The combination with a rock drill having a cylinder, of an attachment adapted to be secured to the cylinder, said attachment having a rectangular recess, a jaw secured in fixed position in one side of the recess, and a second jaw adjustable in the opposite side of the recess to cooperate with the first said jaw for loosely guiding a broaching tool and for retaining such broaching tool in the attachment, said jaws being supported by the front end of the attachment. 65

2. The combination with a rock drill having a cylinder, of an attachment adapted to be secured to the cylinder, said attachment having a front end wall with a rectangular recess, said recess having parallel walls, a jaw secured in fixed position in one side of the recess, said jaw being supported by the end wall, a second jaw in the opposite side of the recess slidable on the end wall and means slidable longitudinally in the attachment for imparting transverse movement to the second said jaw. 80

3. The combination with a rock drill having a cylinder, of an attachment adapted to be secured to the cylinder, said attachment having a recess near its front end, a jaw secured fixedly in one side of the recess to form a guide for one side of a broaching tool adapted to reciprocate loosely in the attachment, a slidable jaw in the other side 95 of the recess to form a guide for the opposite side of such broaching tool and having a tapered side, a wedge interlocked with the slidable jaw, said wedge being slidable in a plane parallel to the longitudinal axis of 100 the front head, and slidable on the tapered side for actuating said slidable jaw transversely in the front head, and means including a bolt and a nut for locking the wedge and the slidable jaw in placed position. 105

In testimony whereof I have signed this specification.

RAYMOND H. SMICKLE.
